UNITED STATES PATENT OFFICE.

VICTOR A. BENSON, OF LOS ANGELES, CALIFORNIA.

ADJUSTABLE DOOR-HANGER.

No. 908,836.

Specification of Letters Patent.

Patented Jan. 5, 1909.

Application filed January 16, 1908. Serial No. 411,161.

To all whom it may concern:

Be it known that I, VICTOR A. BENSON, a citizen of the United States, residing at Los Angeles, in the county of Los Angeles and 5 State of California, have invented a new and useful Adjustable Door-Hanger, of which the following is a specification.

This invention relates to adjustable door hangers, and, while designed especially for 10 elevator doors, is of great advantage when used on other kinds of sliding doors.

The main object of the invention is to positively keep the wheels in absolute alinement with the door, and to provide a device which, 15 in its application to the door, does not require adjustments to aline the wheels with the door, the alinement being always secured upon attaching the device to the door.

Another object is to provide a device of 20 the character described which may readily be adjusted so that the door will hang in a perfect vertical position at right angles to the track, or may be adjusted so that the stile of the door will lie parallel with the casting or jamb of the door way should the latter 25 be out of plumb.

Another object is to provide a device of the character described which may be constructed cheaper than a set of door hangers of ordinary 30 construction and which may be applied to the door with greater facility and in much less time and with less fitting than required for ordinary door hangers.

The accompanying drawings illustrate the 35 invention, and referring thereto:—Figure 1 is a front elevation of an elevator door equipped with the invention. Fig. 2 is an enlarged section on line x^2-x^2 Fig. 1. Fig. 3 is a section on line x^3-x^3 Fig. 2. Fig. 4 is a 40 perspective in detail of the connection bolt. Fig. 5 is a front elevation of a modified form of hanger, showing only the upper portion of the door to which it is attached. Fig. 6 is a front elevation of another form, showing 45 only the upper portion of the door to which the hanger is attached.

In the preferred form, 1 designates the door having a top frame bar 2.

3 is a hanger bar, formed preferably of a 50 single piece of metal, which extends substantially the full width of the door and has downturned ends 4. Journaled near each end of the hanger bar 3 are wheels 5 with grooved peripheries which travel on the 55 track 6.

It will be noted that the wheels 5 are both

journaled to the bar 3, and as this is a rigid member from end to end the two wheels properly journaled therein are fixed in alinement with respect to the bar 3 and cannot 60 work loose or come out of alinement.

The ends 4 of the bar 3 may be attached to the door 1 by means of connection bolts, one of which is shown in detail in Fig. 4. In its preferred form, each connection bolt 65 comprises a threaded stud 7, formed at its upper end with a flattened wing 8, the latter having a laterally projecting stud 9, and immediately below the stud 9 the wing 8 is provided with a perforation 10. The wing 70 8 lies flatly against the downturned end 4 of the hanger bar 3 and its stud 9 is received in a hole formed in the end 4. A screw 11 passes through the orifice 10 and is screwed into the end 4, and this construction rigidly 75 attaches the connection bolt to the end 4. The stud 9, as will be noted, is made sufficiently heavy to carry the weight of the door 1, the screw 11 being relieved of the weight and serving mainly to detachably secure the 80 wing 8 to the member 4. Riveted to the top bar 2 of the door are two bracket plates 12, each being arranged underneath the associated connection bolt, and each bracket plate 12 is provided with a screw threaded 85 opening to receive the threaded stud 7 of the connection bolt, the latter being screwed into the bracket plate 12 before its wing 8 is attached to the member 4. The wing 8 when detached from member 4 permits the 90 connection bolt to be turned in the bracket 12 to adjust the elevation of the wing 8 with respect to the top bar 2, and after the proper vertical adjustment has been made the wing 8 is secured to the member 4. This construction permits either side of the door to 95 be adjusted vertically with respect to the hanger bar 3 to bring the door plumb or into parallelism with the door-way.

The guard plate 13 is formed with a corner 100 nut 14 which is screwed on the stud 7 and has a lateral lug 15 to receive a screw 16, the latter being screwed into the bracket plate 12. When in position, the guard plate 13 projects under the lower edge of the track 105 rail 6, as clearly shown in Fig. 2, and lies close to the under edge, its purpose being to prevent the door from jumping up sufficiently to permit the wheels 5 to ride off from the track. It is obvious that the guard 110 plate 13 may be screwed up or down on the stud 7 to adjust it to the desired position

under the track rail 6, the screw 16 serving to hold the guard plate 13 from turning on the stud 7 after it has been adjusted to the desired position.

5 The modified structure in Fig. 5 is similar in every way to the construction previously described, except that the hanger bar 3 is formed of two sections 3^a and 3^b which are united by a central bar 17, the latter being 10 riveted to the members 3^a and 3^b. The object of this construction is to enable the hanger to be constructed in large quantities without regard to specified dimensions of different widths of doors. In applying the 15 hanger thus constructed, it is quickly fitted to the proper width of door by cutting the central bar 17 of the requisite length, after which the members 3^a and 3^b are riveted thereto, the structure resulting being virtually the same as the form shown in Fig. 3 20 with the two wheels both secured to a rigid horizontal member.

In the modified construction shown in Fig. 6, the hanger bar 3 is dispensed with 25 and the connection bolts are formed with a long wing 18 to which the wheels 5 are journaled. In this form, even though the hanger bar 3 is dispensed with, the advantages of the connection bolt construction are 30 retained.

What I claim is:—

1. In combination with a door, a hanger

therefor comprising a bar extending along the top of the door, wheels journaled in opposite ends of the bar, connection bolts 35 adjustably securing the door to the ends of said bar, a track rail supporting the wheels, and a guard plate screwed on each connection bolt and extending under the track rail.

2. In a door hanger, a wheel, a member in 40 which the wheel is journaled and having an orifice, a connection bolt comprising a threaded stud formed with a flat wing, a stud on the wing projecting into said orifice and a screw passing through the wing into 45 said member, and means on the door in which said threaded stud is screwed.

3. In a door hanger, a wheel adapted to travel on the track rail, means in which the wheel is journaled, a threaded stud on said 50 means, a guard plate screwed on said stud and extending under the track rail, said guard plate having a lateral lug, means on the door in which said stud is screwed, and a clamping screw through said lateral lug 55 into the last means.

In testimony whereof, I have hereunto set my hand at Los Angeles, California, this 6th day of January 1908.

VICTOR A. BENSON.

In presence of—

G. T. HACKLEY,

FRANK L. A. GRAHAM.
